UNITED STATES PATENT OFFICE

WILLIAM P. HORNBUCKLE AND ROBERT F. CRAIG, OF STANLEY, NORTH CAROLINA

BEAM DYEING MACHINE

Application filed December 6, 1924. Serial No. 754,369.

The invention comprises improved apparatus for dyeing or otherwise treating yarn or other material in wound masses.

In the drawings:

5 Figure 1 shows in top plan, beam dyeing apparatus embodying the invention, parts being broken away; Figure 2 is a vertical section wherein most parts appear in elevation, some portions of the structure being 10 broken away; Figure 3 is a vertical section through one of the valve mechanisms; Figure 4 is a horizontal section on the line 4—4 of Figure 3.

In Fig. 2 of the drawings, 1 is a support, 15 for the carrying of any desired number of kiers 2, each of the latter being shown as having its top covered by a hinged lid 3 held closed by clamping means 4. Each kier is constructed at its base with a transversely 20 extending partition 5 having a central opening, and with a tube 6 extending between the partition and the bottom of the kier. The kier contains the usual chamber 7, above the partition, and an annular compartment 8, 25 below the partition, the transversely extending partition having any desired number of openings 9 serving to establish communication between the chamber 7 and the compartment 8. The numeral 10 marks a loom 30 beam including a foraminous body 11 and heads 12, only one of such heads being shown, it having a short tubular extension resting in a depressed seat on the partition 5 around the central opening of the latter, 35 and the beam being clamped in place by the lid 3, if desired.

With the bottoms of the kiers 2 are assembled depending connections 15, communicating with the tubes 6 and with a pipe 16 40 extending lengthwise of the series of kiers. Lateral connections 17 on the kiers 2 establish communication between the compartments 8 and a pipe 18 the latter also extending lengthwise of the series of kiers. A 45 valve casing 19 is provided. A branch pipe 20 leads from the pipe 16 to one side of the valve casing 19. Steam may be introduced into the pipe 20 through a pipe 21. A branch pipe 22 extends between the 50 pipe 18 and the opposite side of the valve

casing 19. The parts 15—16—20—22—18—17 may be alluded to as a first conduit in communication at one end with the kier and the beam, centrally of the latter and in communication at the other end through the 55 opening 9 with the space between the wall of the kier and the body 11 of the beam occupying the kier.

A pipe 23 extends between the lower portion of the valve casing 19 and a pump 26. 60 A pipe 27 extends between the pump and the side portion of the valve casing 19. The pipes 27 and 23 constitute a pump conduit wherein the pump 26 is interposed, the casing 19 being interposed both in the pump conduit, and in the first conduit above defined. The pipe 23 has a lateral branch 24 at a point between the pump 26 and the casing 19 and under the control of a hand valve 25. A pipe 28 branched off from the pipe 70 27 extends to the bottom of a mixing tank 30 wherewith the pipe 28 communicates, the mixing tank being carried by the support 1. A check-valve 29 in pipe 28 closes toward the said mixing tank. Liquid contained in the tank 30 passes into the circulatory system of the apparatus through the pipe 28, the check-valve 29 preventing liquid from being expelled from the interior of the apparatus upward through pipe 28 into the mixing tank by internal pressure of steam within the apparatus when steam is admitted into the kier through pipes (not shown) for heating up the liquid as customary in practice.

A valve 33 is rotatable in the casing 19 and is operated by a stem 34. The valve 33 has a transverse passage 35 which extends about half way around the valve, circumferentially thereof. The valve 33 has an L-shaped passage 36 which opens at one end through the side of the valve, and at the other end through the bottom of the valve.

When the valve 33 is disposed as shown in Figures 3 and 4, the passage 36 in the valve 95 is in communication with the pipes 20 and 23, the passage 35 being in communication with the pipes 27 and 22. Then there is established a circuit comprising the pump 26, the pipe 23, the passage 36 in the valve 33, 100

the pipe 20, the pipe 16, the couplings 15, the tubes 6 in the kiers 2, the beams 10, the chambers 7, the openings 9, the annular compartments 8, the couplings 17, the pipe 18, 5 the branch pipe 22, the passage 35 in the valve 33, the pipe 27 and the pump 26. By the circulation established thereby the dye is caused to pass from the center of the beams outwardly through the thickness of the material upon 10 the beams.

When it is desired to secure a reversal in the direction of the flow of the dye, that is to say, from the chambers 7 inwardly through the material on the beams to the central openings of the beams, the valve 33 is so set that the passage 35 communicates with the pipes 27 and 20, the passage 36 communicating with the pipes 23 and 22. Then there is established a circuit comprising the pump 26, 20 the pipe 23, the passage 36 in the valve 33, the pipe 22, the pipe 18, the couplings 17, the annular compartments 8, the openings 9, the chamber 7, the material wound on the barrels 11 of the beams 10, the tubes 6, the connections 15, the pipe 16, the pipe 20, the passage 35, the pipe 27 and the pump 26.

From the two paragraphs last preceding it will be obvious that a flow from the inside of a beam 10 to the outside thereof, or from the 30 outside of the beam to the inside thereof, may be secured at the will of an operator, a thorough dyeing of the yarn on the body 11 of the beam being secured, and it being unnecessary to unwind the yarn from the section beam in 35 order that the yarn may be dyed.

Suppose that it is desired to draw off the dye. Then the valve 33 is so set that the passage 36 does not communicate with the pipe 20, 22, or 27, but is closed at its upper end 40 by the wall of valve-casing 4, as will be apparent from Fig. 4, the passage 35 communicating with the pipes 20, 22 and 27. The dye from the kiers 2 flows through the pipes 18 and 16. From the pipe 18, the dye passes 45 through the pipe 22, and from the pipe 16, the dye passes through the pipe 20. From the pipes 20 and 22, the dye traverses the passage 35 in the valve 33 and, flowing through the pipe 27, is carried by the pump 26 into that 50 portion of the pipe 23 which is adjacent to the pump 26, the dye flowing away, to any suitable place of storage or discharge, through the pipe 24, the valve 25 having been opened.

55 Air under pressure may be introduced into the pipe 20 through a pipe 21 for the purpose of expelling some of the dye liquor from the material carried by the beams, after the completion of the dyeing operation and following the emptying of the kiers of dye liquor.

The lid 3 of every kier 2 carries an inverted U-shaped pipe 31 wherein a hand-valve 32 is interposed, the said pipe 31 extending downwardly into the top of the mixing tank 30. Only one pipe 31 and its valve

32 are shown. One function of the pipes 31 is to vent the kiers 2 whilst the machine is being filled with water or dye liquor; another is to let entrapped air escape from the contents of the kiers; another is to permit increase or expansion of the water or dye liquor within one or more of the kiers resulting from condensation of live steam therein in boiling-out or in heating-up the dye liquor; another is to provide for flow of liquor from the kiers into the mixing tank 30 and into the kiers again for the purpose of circulation through the mixing tank and kiers; another is to provide an air-vent to facilitate drawing-off the liquid contents of the kiers. By means of valve 32 the rate of feed through pipe 31 may be regulated, and thereby the rate of the circulation through the mixing tank and kiers. One or more of the pipes 31 may be opened now and then to permit a little dye to run through the same into the mixing tank 30, so that the attendant may ascertain, by noting the color thereof, how much the liquor has decreased in strength through absorption of the dye by the material operated upon.

What is claimed is:—

1. In dyeing, etc., apparatus comprising a kier constructed to receive a support for a wound mass, and a conduit having a branch which communicates with the interior of the kier and with the interior of the said wound mass, and having also a second branch communicating with the interior of the kier externally of the wound mass, the combination therewith of a valve-casing having three ports in its shell, with one of which one of said conduit-branches communicates and with a second of which the other of said branches communicates, a pump, a pump-conduit having one branch in communication with the third port of the said shell, and a valve-cylinder rotatably mounted within said casing having a through-way including a port in one end of such cylinder in register with a second branch of said pump-conduit and a lateral port adapted to register in different angular positions of the cylinder with the two ports first mentioned of the valve-casing, alternately, and a second through-way which in the different angular positions of the valve-cylinder connects the first and second ports of the valve-casing, alternately, with the said third port and thereby with the pump-conduit branch first mentioned leading to the pump.

2. The combination with a closed kier adapted to receive material to be operated upon, a conduit system for the circulation of fluid, said system in communication with said kier, means for forcing the fluid to circulate through said system and said kier, a tank, a pipe through which said tank supplies liquid to said system, and a check-valve in connection with said pipe for preventing the

fluid from being expelled back through the pipe to the tank by back pressure within the apparatus.

5 In testimony that we claim the foregoing as our own, we have hereto affixed our signatures.

WILLIAM P. HORNBUCKLE.
ROBERT F. CRAIG.
